No. 826,160.

PATENTED JULY 17, 1906.

G. F. HALL.
WINDOW DRESSER.
APPLICATION FILED NOV. 9, 1905.

UNITED STATES PATENT OFFICE.

GEORGE F. HALL, OF JERSEY CITY, NEW JERSEY, ASSIGNOR, BY MESNE ASSIGNMENTS, TO UNIVERSAL NOVELTY COMPANY, A CORPORATION OF NEW JERSEY.

WINDOW-DRESSER.

No. 826,160.

Specification of Letters Patent.

Patented July 17, 1906.

Application filed November 9, 1905. Serial No. 286,468.

To all whom it may concern:

Be it known that I, GEORGE F. HALL, a citizen of the United States, residing at Jersey City, in the county of Hudson and State 5 of New Jersey, have invented certain new and useful Improvements in Window-Dressers; and I do hereby declare the following to be a full, clear, and exact description of the invention, such as will enable others skilled 10 in the art to which it appertains to make and use the same, reference being had to the accompanying drawings, and to figures of reference marked thereon, which form a part of this specification.

15 This invention has reference generally to improvements in that class of devices known as "window-dressers" or "window-reachers," and the present invention relates more particularly to a simply-constructed device of the 20 character hereinafter more fully set forth, comprising a pair of readily-manipulated and frictionless grips or jaws which are actuated by means of a long shank arranged in a tubular handle and rod for automatically retaining 25 their grip upon the smallest and flimsiest article, such as a lace handkerchief and the like, a lever which is connected with the handle so as to be grasped in the hand with the handle being used to actuate the long shank 30 and the jaws, and a spring or other suitable means being employed to return the various parts to their normal initial positions as soon as the pressure is removed from the lever.

Other objects of this invention not at this 35 time more particularly enumerated will be clearly evident from the following detailed description of my present invention.

The invention consists, primarily, in the novel window-dresser or window-reacher 40 hereinafter set forth, and, furthermore, this invention consists in the various arrangements and combination of parts, as well as in the details of the construction of the same, all of which will be hereinafter more fully set 45 forth and then finally embodied in the clauses of the claim, which are appended to and which form an essential part of this specification.

The invention is clearly illustrated in the 50 accompanying drawings, in which—

Figure 1 is a view of the window-dresser, partly in elevation and partly in section, the movable parts of the device being shown in

their normal initial positions; and Fig. 2 is a side view of the grips or jaws and a sectional 55 representation of the upper framework and the tubular rod in which said grips or jaws are operatively arranged. Fig. 3 is a transverse section taken on line 3 3 in said Fig. 1 looking in the direction of the arrow X; and 60 Fig. 4 is a similar section taken on line 4 4 in said Fig. 1, also looking in the direction of the arrow X. Fig. 5 is a horizontal section on an enlarged scale, said section being represented as being taken on line 5 5 in Fig. 2 of the 65 drawings; and Fig. 6 is a perspective view of the upper portion of the long actuating-rod and its means for actuating the grips or jaws.

Similar characters of reference are employed in the above-described views to indicate 70 corresponding parts.

Referring now to the several figures of the drawings, the reference character 1 indicates the complete implement. 2 is a suitable handle, and 3 a tubular rod extending from 75 one end and preferably from within a tubular portion 4 of said handle, as clearly indicated in Fig. 1 of the drawings. The lower portion of the said handle is provided with a laterally-extending slot or opening 5 and with a tubular portion 6, in which is arranged a tube-like 80 device or member 7, having its lower screw-threaded end portion 8 extending beyond the lower end of the said handle, a socketed nut or cap 9 being screwed upon said end portion 85 8 and against the end of the handle, as shown. A finger 10 on said member 7 extends through the said slot or opening 5, said finger being provided with a bifurcated end portion 11 and a pivotal pin 12. Directly 90 beneath the said finger the said member 7 is also made with an opening or slot 13. Pivotally arranged upon the said pin or pivot 12, so as to be movably connected with the said finger 10, is an actuating-lever 14, said 95 lever being provided with an extension 15, which extends into and through the said slots 5 and 13 and has a bifurcated end portion 16, embracing the lower and screw-threaded part 18 of a long shank 17 and resting in engagement upon a nut 19, adjustably secured upon 100 said screw-threaded part 18. Encircling that portion of the screw-threaded part 18 below the nut 19 and extending from the lower tubular end portion of the tubular member 7 105 into the socket of the said nut or cap 9 is a

coiled spring 20. Suitably secured upon opposite sides of the upper portion of the said tubular rod 3, preferably by being brazed thereto, are the end members 22 of a pair of supporting frames or plates 21. The said plates 21 are each made with an outwardly-bent central portion 23, as illustrated in the several figures of the drawings. The said plates 21 are suitably secured together by means of pins or rivets 24, and that there may be a space between said plates a perforated disk or washer 25 is arranged upon each pin or rivet 24, as shown.

The previously-mentioned long shank 17, which receives a downward movement within the tubular rod 3 and said member 7 when the lever 14 is pressed toward the side of the handle 2, has its upper end extending from the upper part of said tube 3 and between the said plates 21, a pair of preferably T-shaped members 26 being secured on opposite sides of said shank, substantially as shown. The oppositely-extending portions 27 of said members 26 are united by means of pins or rivets 28, upon each of which is rotatively arranged a roller 29. Other connecting pins or rivets 30 are arranged at the respective ends of said plates 21, an antifriction-roller 31 being arranged upon each pin or rivet 30 between the said plates 21. Pivotaly arranged upon each roller 31 is a bell-crank comprising a pair of butts or arms 32 and 33, one of which, as 32, is provided with a grip or grasping-jaw 34, and the other butt or arm 33 being made with a slotted or bifurcated end portion 35, operatively fitted over a roller 29 upon the pin or rivet 28. These various parts are all of them operatively connected in a manner substantially as illustrated in the several figures of the drawings, and their operation, briefly, is as follows: When the handle 2 is grasped in the hand and the lever 14 is forced in a direction toward said handle, a downward movement of the finger 15 forces the long shank 17 downwardly within the tubular rod 3 and member 7, whereby the spring 20 becomes depressed. At the same time the downward movement of the device 26 and the rollers 29 produce a pivotal action of the two bell-cranks toward each other, thereby causing their grips or grasping-jaws 34 to tightly grasp an article placed between them and to be carried between said closed jaws from place to place for the purpose of dressing a store-window or for reaching an article from a shelf or for placing such article upon the shelf or other desired place. As soon as the article has been placed the operator releases the lever 14 by removing the pressure therefrom, which permits the coils of the compressed spring 20 to assume their normal relation, thereby causing the movable parts of the implement to once more assume their normal initial positions at rest, as shown in Fig. 1 of the drawings.

From the foregoing description of my invention it will be clearly seen that I have devised an efficient device which is especially adapted to dressing show-windows, the implement being admirably adapted to enable an operator to change the arrangement of the goods at will and to place articles in the most inaccessible parts without the use of a ladder or the like. The device may also be used for removing articles from lofty shelves, ceilings, and other points which cannot ordinarily be reached.

Having thus described my invention, what I claim is—

1. In a window-dresser, a tubular shank and handle, a tubular member in said tubular handle, said member and handle having registering openings, a finger on said member, said finger extending through said openings, a rod movably arranged in said tubular shank and tubular member, a pair of normally open jaws connected with said rod, and a lever pivotally connected with said finger for actuating said rod and producing a downward movement of said rod, to close said jaws upon an article, substantially as and for the purposes set forth.

2. In a window-dresser, a tubular shank and handle, a tubular member in said tubular handle, said member and handle having registering openings, a finger on said member, said finger extending through said openings, a rod movably arranged in said tubular shank and tubular member, a pair of normally open jaws connected with said rod, and a lever pivotally connected with said finger for actuating said rod and producing a downward movement of said rod, to close said jaws upon an article, and a spring for returning said rod upwardly and separating said jaws when said rod-actuating means is released, substantially as and for the purposes set forth.

3. In a window-dresser, a reciprocating rod, a pair of plates at the upper end of said rod, said plates being formed with a space between them, and oscillatory bell-cranks provided with grasping-jaws at one end and slotted portions at the other ends extending between said plates, and means between said plates in engagement with said slotted portions of the bell-cranks, substantially as and for the purposes set forth.

4. In a window-dresser, a reciprocating rod, a pair of plates at the upper end of said rod, said plates being formed with a space between them, and oscillatory bell-cranks provided with grasping-jaws at one end, and slotted portions at the other ends extending between said plates, and rollers arranged between said plates in engagement with said slotted portions of said bell-cranks, substantially as and for the purposes set forth.

5. In a window-dresser, a tubular shank, a grip-carrying frame upon said shank, comprising a pair of plates having a space be-

tween them, bell-cranks pivoted between said plates, said bell-cranks being provided with grasping-jaws at one end and slotted portions at the other ends, a reciprocatory rod in said tubular shank, a pair of plates at the upper end of said rod, said plates being formed with a space between them, and means between said plates in engagement with the slotted portions of the bell-cranks, substantially as and for the purposes set forth.

6. In a window-dresser, a tubular shank, a grip-carrying frame upon said shank, comprising a pair of plates having a space between them, bell-cranks pivoted between said plates, said bell-cranks being provided with grasping-jaws at one end and slotted portions at the other ends, a reciprocatory rod in said tubular shank, a pair of plates at the upper end of said rod, said plates being formed with a space between them, and rollers arranged between said plates in engagement with said slotted portions of said bell-cranks, substantially as and for the purposes set forth.

7. In a window-dresser, a tubular shank, a grip-carrying frame upon said shank, comprising a pair of plates having a space between them, antifriction-rollers between said plates, bell-cranks pivoted on said rollers, said bell-cranks being provided with grasping-jaws at one end and slotted portions at the other ends, a reciprocatory rod in said tubular shank, a pair of plates at the upper end of said rod, said plates being formed with a space between them, and rollers arranged between said plates in engagement with said slotted portions of said bell-cranks, substantially as and for the purposes set forth.

8. The herein-described window-dresser, comprising a tubular shank and handle, a tubular member in said tubular handle, said member and handle having registering openings, a finger on said member, said finger extending through said openings, a grip-carrying frame upon said shank, comprising a pair of plates having a space between them, antifriction-rollers between said plates, bell-cranks pivoted on said rollers, said bell-cranks being provided with grasping-jaws at

one end and slotted portions at their other ends, a reciprocatory rod in said tubular shank and tubular member in said handle, a pair of plates at the upper end of said rod, said plates being formed with a space between them, rollers arranged between said plates in engagement with said slotted portions of said bell-cranks, and a lever pivotally connected with said finger for actuating said reciprocatory rod and producing a downward movement of said rod, to close the jaws of the bell-cranks upon each other, substantially as and for the purposes set forth.

9. The herein-described window-dresser, comprising a tubular shank and handle, a tubular member in said tubular handle, said member and handle having registering openings, a finger on said member, said finger extending through said openings, a grip-carrying frame upon said shank, comprising a pair of plates having a space between them, antifriction-rollers between said plates, bell-cranks pivoted on said rollers, said bell-cranks being provided with grasping-jaws at one end and slotted portions at their other ends, a reciprocatory rod in said tubular shank and tubular member in said handle, a pair of plates at the upper end of said rod, said plates being formed with a space between them, rollers arranged between said plates in engagement with said slotted portions of said bell-cranks, and a lever pivotally connected with said finger for actuating said reciprocatory rod and producing a downward movement of said rod, to close the jaws of the bell-cranks upon each other, and a spring for returning said rod upwardly and separating said jaws when said rod-actuating means is released, substantially as and for the purposes set forth.

In testimony that I claim the invention set forth above I have hereunto set my hand this 27th day of October, 1905.

GEORGE F. HALL.
